UNITED STATES PATENT OFFICE.

ALFRED SABEN MARTIN, OF FORT VALLEY, GEORGIA, ASSIGNOR OF ONE-HALF TO WALTER H. SAWYER, OF SAME PLACE.

GRINDING-MILL.

SPECIFICATION forming part of Letters Patent No. 390,497, dated October 2, 1888.

Application filed January 8, 1887. Renewed June 25, 1888. Serial No. 278,209. (No model.)

To all whom it may concern:

Be it known that I, ALFRED SABEN MARTIN, a citizen of the United States, and a resident of Fort Valley, in the county of Houston and State 5 of Georgia, have invented certain new and useful Improvements in Grinding-Mills; and I do hereby declare that the following is a full, clear, and exact description of the invention, which will enable others skilled in the art to 10 to which it appertains to make and use the same, reference being had to the accompanying drawings, which form a part of this specification, and in which—

Figure 1 is a side view of my improved 15 grinding-mill. Fig. 2 is an end view of the same. Fig. 3 is a longitudinal vertical sectional view. Fig. 4 is a transverse sectional view. Fig. 5 is a top view showing the lines $x x$ and $y y$, on which the two sectional views, 20 respectively, are taken. Fig. 6 is a perspective view of the grinding-disk with one cutter or grinding-block removed, and Figs. 7 and 8 are detail views of the grinding-block and one of the stationary disks.

25 Similar numerals of reference indicate corresponding parts in all the figures.

My invention has relation to that class of 30 grinding-mills in which a revolving grinding-disk having a horizontal shaft is journaled between two stationary disks, the said disks having grinding blocks or cutters inserted in their faces; and it consists in the improved 35 construction of the disk and grinding-blocks of such a mill, as will be hereinafter more fully described and claimed.

In the accompanying drawings, which show a complete mill, to more clearly illustrate the application and workings of the parts referred to above and claimed as my invention, the 40 numerals 1 indicate the four supporting-legs of the frame, which legs are connected by means of side pieces, 2, and end pieces, 3, and at their upper ends by means of a hopper, 4, having the end pieces, 5, inclined toward the 45 middle.

A shaft, 6, is journaled transversely in bearings 7 upon the side pieces, and the drive-pulley 8, to which the power is applied, is secured upon one end of the shaft, a smaller pulley, 9, 50 being secured upon the shaft inside of the drive-pulley.

The revolving grinding-disk 10 is secured upon the middle of the shaft, and is thinner at its periphery than at its center, and is provided with radiating slots 12, extending from 55 the periphery to near the shaft, blocks 11 being formed at the inner ends of the slots.

Recesses 13 are formed in the periphery of the disk at the outer ends of the slots, and grinding-blocks 14 fit in the slots, having 60 notches 15 in their inner ends, and having beveled side edges, 16, which project outside of the face of the disk, forming cutters or grinding-ribs, and lips 17 at the outer ends of the blocks fitting into the recesses in the periphery 65 of the disk.

Two stationary segmental disks, 18, are supported at the sides of the grinding-disk, having removable grinding-blocks 19 in their inwardly-inclined faces, about one-third of said 70 disks being cut away, leaving about one-third of the revolving grinding-disk uncovered. The stationary disks are provided with longitudinal bars 20, projecting to both ends of the supporting-frame, and the ends of these bars are 75 perforated and fit with the said perforations upon screw-threaded bolts 21, secured horizontally in the legs of the frame and projecting transversely from the same, and nuts 22 fit upon these bolts and serve to adjust the 80 bars thereon, drawing the disks nearer to or farther away from the faces of the grinding-disk.

The hopper is formed with a casting, 23, covering the aperture in the lower end of the 85 hopper, and this casting is formed with two longitudinal slots or apertures, 24, which register with the faces of the grinding-disk, so that any grain or seed fed through them will drop between the revolving grinding disk or 90 runner and the stationary disks.

A shaft, 25, is journaled transversely in the hopper, and is provided with downwardly-projecting radiating stirrer-fingers 26, projecting toward and into the slots in the casting, 95 and one end of the shaft is provided with a crank, 27, to which is pivoted a connecting-rod, 28, pivoted to the face of a pulley, 29, journaled upon a stub-axle upon the side of the frame, and having a belt, 30, passing around 100 it and around the smaller pulley upon the grinding-shaft. It will thus be seen that when the

driving-shaft is revolved the runner or grinding-disk will be revolved and the grain or seed which may be fed between the disks will be crushed and cut by the beveled ribs formed 5 upon the faces of the disks by the grinding-blocks, the ribs of the revolving disk being faced in a direction opposite to the ribs of the stationary disks, so as to bring the edges to face each other.

- 10 By having the grinding-blocks removable the edges may be sharpened, and the blocks may be removed and others substituted when the blocks become so much worn that they cannot be sharpened any more, and by the shape 15 of the blocks in the revolving disks the said blocks need no fastening, but will be perfectly held in place in their slots by the notched inner ends fitting upon the blocks and by the lips resting in the recesses in the periphery of the disk.
- 20 As the grinding-shaft revolves, the pulley 29 upon the frame will be slowly revolved and will impart a rocking movement to the shaft having the stirring-fingers, which will serve to force the grain or seed into the slots or apertures in 25 the hopper, the machine being thus enabled to grind any grain or seed regardless of its tendencies to stick together and form lumps, enabling the machine to grind cotton-seed.

By turning the adjusting-nuts upon the bolts 30 the stationary disks may be moved toward or from the revolving disk, regulating the degree of fineness to which the grain or seed is to be ground.

The disks are preferably covered with a hood or casing, which prevents the grain or seed from flying out from the disks, and thus be wasted before being perfectly ground. The lower portions of the stationary disks are held adjusted by means of bolts 32 passing through 35 the side pieces of the supporting-frame, and having nuts 33 upon them, by means of which 40 they may be drawn in or out, as desired.

Having thus described my invention, I claim and desire to secure by Letters Patent of the United States—

In a grinding-machine, the combination of a grinding disk thinner at its periphery than at its center, and having radiating slots extending from the periphery to near the center, having recesses at the outer ends, and having 45 blocks in the inner ends with grinding-blocks fitting in the slots, and having notches in their inner ends fitting upon the blocks in the ends of the slots, and having lips at the outer ends fitting in the recesses and formed with beveled 50 side edges, having their sharp edges projecting above the faces of the disk, as and for the purpose shown and set forth.

In testimony that I claim the foregoing as my own I have hereunto affixed my signature 55 in presence of two witnesses.

ALFRED SABEN MARTIN.
